(57) **CLAIM**

The ornamental design for a shirt, as shown and described.

DESCRIPTION

FIG. 1 is a front perspective view of a shirt having a left border and no left sleeve and a right cap sleeve, showing my new design;

FIG. 2 is a rear perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top elevational view thereof; and,

FIG. 8 is a bottom elevational view thereof.

In the drawings, the "+" and ":" symbols are included for the purpose of illustrating a contrast of appearance of the claimed design.

1 Claim, 2 Drawing Sheets
